UNITED STATES PATENT OFFICE.

JOSEPH GALAMB, OF DETROIT, MICHIGAN, ASSIGNOR TO FORD MOTOR COMPANY, OF DETROIT, MICHIGAN, A CORPORATION OF MICHIGAN.

RADIATOR.

Specification of Letters Patent. Patented Mar. 16, 1920.

1,334,269.

Application filed October 22, 1917. Serial No. 197,764.

To all whom it may concern:

Be it known that I, JOSEPH GALAMB, a citizen of the United States of America, residing at Detroit, in the county of Wayne and State of Michigan, have invented certain new and useful Improvements in Radiators, of which the following is a specification, reference being had therein to the accompanying drawings.

10 This invention relates to radiators for automobiles and to an arrangement thereof whereby the radiator is rigidly supported and whereby a casing is provided that is not heated appreciably by the radiator body proper, so that the finish of the radiator frame is not impaired.

15 The invention consists in the matters hereinafter set forth, and more particularly pointed out in the appended claims.

20 In the drawings,

Figure 1 is a view, partially in rear elevation and partially in section of a radiator embodying features of the invention, and

Fig. 2 is a view in section taken on or 25 about line II—II of Fig. 1.

As herein indicated, as one preferred form of invention a radiator core 1 of any preferred design, herein shown as upright water tubes 2 and cross fins 3, connects an upper header 4 with a lower header 5. A 30 filler nipple 6 for the upper header and appropriate connections 7 and 8 for pipe leading to the water jacket are also provided.

The lower header 5 is supported on brackets 35 9 that are brazed or otherwise made fast thereto, and extend to the laterally projecting portions of a cross stay 10. The latter which is formed rigidly with the rest of the grid or cores, and is in effect an enlarged cross-fin of the core is brazed, riveted or made fast to the outturned portions 11 of these brackets. Thus in effect the entire portion 12 of the grid below the member 10, including the lower header is a rigid base 40 45 which is securely supported as indicated on the channels 13 or like side members of the chassis frame. A jacket 14 is formed to enclose the upper header, the outturned lower portion 15 overlying the extensions 11 of the cross member 10, whereby a single bolt 16 on each side of the radiator secures the jacket and radiator firmly in position on the chassis frame. The jacket is also secured in spaced relation to the upper header 4 both 50 55 by conformation and by being steadied by

the nipple 6 over which it readily drops, the casing or jacket having a depending portion 17 to cover the base.

As will be understood, the tubes and fins 3 constitute the heat-dissipating section of 60 the core unit, the latter of course, including the upper and lower headers. Cross-stay 10 therefore forms a means for supporting the unit on the longitudinal members of the chassis, this means projecting laterally from 65 the sides of the unit and extending into the unit; and since the plate-like formation of the cross stay has a greater length than the transverse width of the unit, the projecting portions of the cross stay produce supporting elements which can overlie or extend 70 into the plane of the chassis members and thereby produce an exceedingly efficient support for the unit.

As a result of this construction a very 75 rigid radiator is obtained that is readily placed in position and is at all times slightly as the hood or jacket is not affected by the heat of the headers and grids because of the air space between the jacket and body of the 80 radiator. Furthermore, the base construction stiffens the entire structure and makes it extremely efficient in resisting road shock.

Obviously, changes in the details of construction may be made without departing 85 from the spirit of my invention and I do not care to limit myself to any particular form or arrangement of parts.

What I claim is:

1. In radiators for motor vehicles, a core 90 unit having means for supporting the unit on the vehicle chassis, said means projecting laterally from the sides of the unit and extending inwardly into the heat-dissipating portion of the unit.

2. In radiators for motor vehicles, a core 95 unit having means for supporting the unit on the vehicle chassis, said means including an element extending in opposite directions from a plane corresponding to a side of 100 the unit to produce a portion extending into the unit formation and a portion extending laterally therefrom to form a supporting structure for the unit.

3. In radiators for motor vehicles, a core 105 unit having means for supporting the unit on the vehicle chassis, said means including an element extending transversely of the unit and having a length greater than the transverse width of the heat-dissipating 110

portion of the unit to produce projecting portions adapted to extend in overlying relation to the longitudinal members of the chassis.

- 5 4. In radiators for motor vehicles, a core unit having means for supporting a unit on the vehicle chassis, said means including a flat plate-like element extending transversely of the unit in a single plane and having a length greater than the transverse width of the heat-dissipating portion of the unit to produce projecting portions adapted to extend over longitudinal members of the chassis.
- 10 5. In radiator construction for motor vehicles, a core unit including upper and lower headers spaced apart and connected together by a heat-dissipating section, and means for supporting the unit on the vehicle chassis, said means projecting laterally from the sides of the unit and extending inwardly into the heat-dissipating section, and intermediate the vertical length of the latter.
- 15 6. In radiator construction for motor vehicles, a core unit including upper and lower headers spaced apart and connected together by a heat-dissipating section, and means for supporting the unit on the vehicle chassis, said means including a plate-like element of greater length than the transverse width of the unit to provide projecting portions which overlie the longitudinal members of the chassis, said element intersecting the vertical length of the heat-dissipating sections.
- 20 7. In radiator construction for motor vehicles, a core unit including upper and lower headers spaced apart and connected together by a heat-dissipating section, an

element intersecting the vertical length of said section at a point spaced from the lower header and having a length to produce projecting portions extending beyond the sides of the unit, and brackets connecting said projecting portions with the lower header to produce a rigid base for the unit.

8. In radiator construction for motor vehicles, a core unit including upper and lower headers, and a heat-dissipating section, said unit also including projections extending laterally from the sides of the unit and extending into the heat-dissipating section, a jacket positionable over and spaced from the unit and having flanges overlying said unit projections, and means for connecting said projections and flanges to the longitudinal members of the vehicle chassis to support the radiator in position.

9. In radiator construction for motor vehicles, a core unit including upper and lower headers, and a heat-dissipating section, said units also including projections extending laterally from the sides of the unit and extending into the heat-dissipating section, brackets connecting the lower header with said projections, a jacket positionable over and spaced from the unit and having flanges overlying said unit projections, and means for connecting said projections, brackets and flanges to the longitudinal members of the vehicle chassis to support the radiator in position.

In testimony whereof I affix my signature in the presence of two witnesses.

JOSEPH GALAMB.
